UNITED STATES PATENT OFFICE.

JOSEPH RICHARD BROADLEY, OF LONDON, ENGLAND.

APPARATUS FOR GRINDING, CLASSIFYING, AND DECANTING ORES.

1,418,523.

Specification of Letters Patent. Patented June 6, 1922.

Application filed September 30, 1920. Serial No. 413,751.

To all whom it may concern:

Be it known that I, JOSEPH RICHARD BROADLEY, a subject of the King of Great Britain, residing at 300 Alexandra Park 5 Road, Wood Green, London, N. 22, England, mechanical engineer, have invented new and useful Improvements in Apparatus for Grinding, Classifying, and Decanting Ores, of which the following is a specification.

10 The object of my invention is to provide an improved construction of machine which will combine the functions of a revolving grinding mill of the type usually known as a ball, pebble or tube mill with those of a 15 hydraulic classifier for the purpose of evacuating the material under treatment (hereinafter termed ore) when it becomes sufficiently fine to permit of decantation by suspension in a rising and overflowing current 20 of water.

My invention includes the use of a cylinder divided into two principal compartments by a diaphragm provided with apertures to permit the passage of water or other liquid 25 with small particles of ore (hereinafter termed pulp) whilst preventing the passage of larger pieces and of the balls, pebbles or other grinding medium.

In the accompanying drawings Fig. 1 is a 30 longitudinal section of a machine in which the secondary compartment is subdivided for reasons hereinafter explained; Fig. 2 is an end elevation of the baffle plate within the secondary compartment as seen from section 35 line A—B in Fig. 1. Fig. 3 is a section on the line C—D in Fig. 1, looking towards the baffle plate; Fig. 4 is a longitudinal section of part of a machine in which the secondary compartment is not subdivided; Fig. 5 is a 40 section on line C—D in Fig. 1, looking towards the right showing means for returning settled sands from the secondary compartment to the primary compartment; Fig. 6, is a section on line E—F in Fig. 1, showing 45 means for subdividing the secondary compartment; Fig. 7, is a section on line G—H in Fig. 1 looking towards the right, showing means for constructing the principal diaphragm and Fig. 8, is a section on line 50 J—K in Fig. 4, showing an alternative means for constructing the principal dia-

phragm.

The primary compartment *a* of the cylinder is used in the ordinary manner to reduce 55 the ore by impact and or by attrition with the grinding medium and the secondary

compartment *b* is provided with means herein described for the purpose of separating the fine particles of ore (hereinafter termed the slimes) from the coarser particles 60 of ore (hereinafter termed the sands) and for decanting the slimes through the discharge outlet *c* by way of the trunnion *d* and for returning the sands by way of the chute 65 *e* and return tube *f* to the primary compartment *a* for further grinding.

The secondary compartment *b* may be either attached to or integral with the primary compartment *a*. It is preferably of cylindrical formation closed at the end by the 70 head member *g* of the cylinder *h* of the mill, with the exception of a central discharge opening giving exit for the slimes which will pass through a hollow supporting trunnion *d* resting in a main bearing *i* carrying 75 the delivery end of the mill.

The secondary compartment *b* is preferably subdivided by an auxiliary diaphragm *j* provided with a port or ports *k* at or near the centre providing passage for pulp collected by a chute or chutes *l* communicating from a position at the inner periphery of the cylinder *h* to the port or ports *k* thus permitting a difference between the levels of 80 pulp on either side of the auxiliary dia- 85 phragm *j*.

A circular baffle plate *m* of a size less than the inner diameter of the secondary compartment *b* will be suitably mounted inside the secondary compartment *b* and concentric therewith a suitable distance from the central discharge opening of the trunnion *d* to protect the approach thereto by partially closing the sectional area of the secondary compartment *b* allowing progress 90 of the pulp from the diaphragm towards the discharge end of the secondary compartment *b* thus forming a weir through which the pulp must flow with change of direction to reach the discharge opening of the trunnion *d*.

The circular baffle plate *m* may be provided with vanes *n* on one or both sides suitably disposed for the purpose of agitating the pulp contained in the secondary 105 compartment *b* to prevent settlement of particles which it may be desired to decant as slimes.

By these means the sands will tend to settle whilst the slimes will rise behind 110 the baffle *m* and escape to the discharge outlet *c* by way of the trunnion *d*.

Attached to or integral with the inner wall of the secondary compartment *b* my invention provides a radial chute or trough *o* which may be of involute formation connecting with the central opening of the return tube *f* allowing passage through the principle diaphragm *p* separating the primary compartment *a* from the secondary compartment *b* for the purpose of collecting and returning sands to the primary compartment *a* for further grinding.

The central opening of the return tube *f* may be extended by lengthening the return tube *f* to project within the primary compartment *a* for the purpose of delivering returned sands to a position in the primary compartment *a* removed from proximity to the diaphragm *p* to prevent immediate re-entry to the secondary compartment *b* and 15 or the central opening of the return tube *f* may be extended by lengthening the return tube *f* to project within the secondary compartment *b* to reach a position beyond the auxiliary diaphragm *j* to make connection with the radial chute or trough *e*. The return trunnion *f* may or may not be attached to 20 or integral with the trunnion *d*.

The secondary compartment *b* is preferably provided with internal projections 30 or vanes *o* attached to or integral with the shell of the cylinder *h* for the purpose of guiding the accumulated sands towards the path of the inlet aperture *g* of the chute or trough *e*.

The principal diaphragm *p* may be constructed substantially as shown in Figs. 1, and 7, having grids *r* providing passages for pulp over a comparatively large portion of the sectional area of the cylinder *h* 40 particularly for the purpose of facilitating the progress of pulp from the primary compartment *a* to the secondary compartment *b*. Alternatively for use particularly when extremely fine grinding of the pulp is desired the principal diaphragm *p* may be constructed substantially as shown in Figs. 4 and 8, having ports *s* near the return trunnion *f* for the purpose of maintaining a comparatively high level of pulp within 45 the primary compartment *a*.

It is often desirable to maintain a low level of pulp in the primary compartment *a* to take advantage of the scouring action of pulp flowing to the secondary compartment *b* for the purpose of quickly removing particles of ore which have already reached the desired fineness and to accomplish this whilst maintaining the necessary level of pulp to provide exit of slimes from 55 the secondary compartment *b* by way of the trunnion *d* my invention provides for the subdivision of the secondary compartment *b* by means of the auxiliary diaphragm *j* with chute or chutes *l* and port or ports *k* as hereinbefore described.

In certain circumstances it may be desirable to subdivide the secondary compartment *b* as herein described for use in conjunction with the alternative construction of the principal diaphragm *p* shown in 70 Figs. 4 and 8.

The primary compartment *a* will be fed with ore in any ordinary manner through a central opening which may be formed by a hollow supporting trunnion *t* resting in 75 a main bearing *u* carrying the feed end of the mill.

Water or other liquid may be introduced with the ore and or by means of a pipe *v* projecting through the discharge trunnion *d* and arranged in any suitable manner. The pipe *v* may terminate behind or pass through the centre of the baffle *m* to deliver water to one or both sides of the baffle *m* for the purpose of diluting the pulp and 85 thereby assisting settlement of sands.

The general construction of the mill and the manner of imparting motion to same excepting as herein described may be according to ordinary practice with machines 90 of any similar type.

What I claim as my invention, and desire to secure by Letters Patent, is:—

1. An ore treating apparatus comprising a rotary cylinder provided at one end with a hollow trunnion constituting an axial ore inlet and at its other end with a hollow trunnion constituting an axial ore outlet, a dividing apertured partition in said cylinder forming on the ore inlet side a grinding 100 chamber adapted to contain grinding balls or pebbles and on the ore outlet side a hydraulic classifying chamber having a water supply and in which the slimes separated by gravity from the sands flow out 105 through the said axial outlet.

2. An ore treating apparatus comprising a rotary cylinder provided at one end with a hollow trunnion constituting an axial ore inlet and at its other end with a hollow 110 trunnion constituting an axial ore outlet, a dividing apertured partition in said cylinder forming on the ore inlet side a grinding chamber adapted to contain grinding balls or pebbles and on the ore outlet side a hydraulic classifying chamber having a water supply and in which the slimes separated by gravity from the sands flow out through the said axial outlet, and a baffle plate in 115 said classifying chamber spaced from the discharge end thereof.

3. An ore treating apparatus comprising a rotary cylinder provided at one end with a hollow trunnion constituting an axial ore inlet and at its other end with a hollow trunnion constituting an axial ore outlet, a dividing apertured partition in said cylinder forming on the ore inlet side a grinding 125 chamber adapted to contain grinding balls or pebbles and on the ore outlet side a hydraulic 130

- classifying chamber having a water supply and in which the slimes separated by gravity from the sands flow out through the said axial outlet, and a baffle plate in said classifying chamber spaced from the discharge end thereof, said baffle plate being equipped with eccentric vanes to form agitators for the pulp.
4. An ore treating apparatus comprising a rotary cylinder provided at one end with a hollow trunnion constituting an axial ore inlet and at its other end with a hollow trunnion constituting an axial ore outlet, a dividing apertured partition in said cylinder forming on the ore inlet side a grinding chamber adapted to contain grinding balls or pebbles and on the ore outlet side a hydraulic classifying chamber having a water supply and in which the slimes separated by gravity from the sands flow out through the said axial outlet, and a baffle plate in said classifying chamber spaced from the discharge end thereof, said baffle plate being in the form of a disk concentric with the classifying chamber with its periphery spaced from the walls of said chamber and provided with eccentric vanes on its opposed faces to form agitators for the pulp.
5. An ore treating apparatus comprising a rotary cylinder provided at one end with a hollow trunnion constituting an axial ore inlet and at its other end with a hollow trunnion constituting an axial ore outlet, a dividing apertured partition in said cylinder forming on the ore inlet side a grinding chamber adapted to contain grinding balls or pebbles and on the ore outlet side a hydraulic classifying chamber having a water supply and in which the slimes separated by gravity from the sands flow out through the said axial outlet, an auxiliary dividing partition in said classifying chamber spaced from said apertured partition and having ports for the passage of the pulp.
6. An ore treating apparatus comprising a rotary cylinder provided at one end with a hollow trunnion constituting an axial ore inlet and at its other end with a hollow trunnion constituting an axial ore outlet, a dividing apertured partition in said cylinder forming on the ore inlet side a grinding chamber adapted to contain grinding balls or pebbles and on the ore outlet side a hydraulic classifying chamber having a water supply and in which the slimes separated by gravity from the sands flow out through the
- said axial outlet, an auxiliary dividing partition in said classifying chamber spaced from said apertured partition and having ports spaced from its periphery with chutes leading from said ports to points adjacent the walls of said chamber to provide for different levels of the pulp on opposite sides of said auxiliary partition.
7. An ore treating apparatus comprising a rotary cylinder provided at one end with a hollow trunnion constituting an axial ore inlet and at its other end with a hollow trunnion constituting an axial ore outlet, a dividing apertured partition in said cylinder forming on the ore inlet side a grinding chamber adapted to contain grinding balls or pebbles and on the ore outlet side a hydraulic classifying chamber having a water supply and in which the slimes separated by gravity from the sands flow out through the said axial outlet, a longitudinally arranged sand return pipe opening at its opposite ends into said classifying and grinding chambers respectively, a radially extending chute leading from the inlet end of said pipe to a point adjacent the wall of the classifying chamber, and riffles on said wall for guiding the sands into said pipe.
8. An ore treating apparatus comprising a rotary cylinder provided at one end with a hollow trunnion constituting an axial ore inlet and at its other end with a hollow trunnion constituting an axial ore outlet, a dividing apertured partition in said cylinder forming on the ore inlet side a grinding chamber adapted to contain grinding balls or pebbles and on the ore outlet side a hydraulic classifying chamber having a water supply and in which the slimes separated by gravity from the sands flow out through the said axial outlet, a longitudinally arranged sand return pipe opening at its opposite ends into said classifying and grinding chambers respectively, a radially extending curved chute leading from the inlet end of said pipe to a point adjacent the wall of said classifying chamber, and convolute riffles on said wall for guiding the sands into said pipe.
